UNITED STATES PATENT OFFICE.

CHARLES F. ZIMMERMANN, OF PHILADELPHIA, PENNSYLVANIA.

HARP.

SPECIFICATION forming part of Letters Patent No. 257,808, dated May 9, 1882.

Application filed December 10, 1881. (No model.)

To all whom it may concern:

Be it known that I, CHARLES F. ZIMMERMANN, a citizen of the United States, resident of the city and county of Philadelphia, in the State of Pennsylvania, have invented certain new and useful Improvements in Harps, of which the following is a specification, reference being had to the accompanying drawings, wherein—

10 Figure 1 is a plan of a harp with my improvements shown as applied thereto. Fig. 2 is an elevation on line 1 1, Fig. 1. Fig. 3 is an enlarged vertical section on line 2 2, Fig. 1. Fig. 4 is a similar view on line 3 3, Fig. 1; and Fig. 15 5 is a broken plan, partly in section, of the appliances constituting my invention, and shown as drawn to an enlarged scale.

My invention has relation to harps, and has for its object to provide a harp with appliances 20 designed and adapted to be operated to come into contact with certain determined strings of such instrument to reduce them to silence and render them incapable of vibrating to give a musical tone during such contact. Such appliances I call "trigger-bars," and they are 25 arranged transversely with the strings of the harp. A harp so provided has the size of a zither, and which I term an "autoharp," and the manner in which the instrument is played 30 is entirely new. The player glides with the thumb of his right hand over all the sounding-strings of the instrument to the tone of the melody, while the different trigger-bars render those strings silent which do not belong to the 35 responsive chord, such trigger-bars simply doing the work of the performer, who does not now need his left hand for the accompaniment, the tones of the different chords being given by the various trigger-bars. Each one of the 40 latter renders certain strings of the autoharp silent, so that the remaining strings compose a certain chord. The more strings and trigger-bars applied to such instrument the more perfect the latter will be. The instrument 45 may be used for accompaniment to the voice or another musical instrument, or the melody may be played at the same time with the accompaniment, as on any other harp.

My invention has for its further object to 50 provide the autoharp with trigger-bars arranged to simultaneously contact with or touch all the

strings of the instrument in the middle of their length, thus temporarily shortening such strings and raising their tone, thereby providing means whereby a melody may be played 55 upon harps in the different octaves. Such trigger-bar I call the "flageolet" trigger-bar, because by its contact with the harp-strings the latter then give the flageolet or falsetto tones when struck. Such trigger must always 60 touch the middle of the strings. This requirement rendered it necessary to change the shape of the common zither to that shown in the drawings, so that such bar can be placed immediately across the middle of each string of 65 the harp.

My invention accordingly consists of a harp shaped as shown in the drawings, and which is provided with two sets of trigger-bars, each such bar being provided with depending fingers located and arranged thereon, so that when the bar is moved said fingers will come in contact with the strings of the instrument for the purpose above set forth.

Referring to the accompanying drawings, A 75 represents my autoharp of the required shape, as shown—*i. e.*, wider in the middle than at its ends, the latter being correspondingly configured. *a a* represent the strings thereof tuned to the natural scale or key. The sides *a' a'* of 80 such harp are provided with receptacles or boxes *B B'*, having partitions or dividing strips *b b'* for forming a series of chambers or bearings in such receptacles. The latter are centrally located upon the harp, as shown, and 85 are adapted for and designed to receive the ends of a series of bars, *C C'*, extending across the harp-strings a slight distance above the same, as indicated in Figs. 3 and 4. Such bars or push-rods, or, as I shall hereinafter term 90 them, "triggers," are provided with push-buttons *c c* and springs *c' c'*, as shown, so that when manual pressure is applied to said buttons said triggers are pushed in their determined paths of movement, the reaction of 95 springs *c' c'* reversely moving such triggers when such pressure is released from said buttons.

The triggers *C C'* are provided on their under sides with a series of depending fingers, *c²* 100 *c²*, located between the harp-strings, as shown in Figs. 3 and 4, and are of such length that

they will engage or contact with the strings when the triggers are moved.

The triggers C C represent the chord-triggers, and are more plainly shown in Fig. 4—5 that is, each said trigger has its depending fingers c^2 c^2 so arranged that when pushed in the direction indicated by arrow x it will reduce to silence or cut out of the natural scale certain strings of the harp or autoharp which 10 do not belong to the chords wanted.

The instrument may have a diatonic scale of fifteen strings or a chromatic scale of thirty or more strings, and accordingly two to seven or more trigger-bars, C. Each of these trigger-bars may render it possible to select two, 15 or even three and four, chords by working such bar one way or the other, it resting between two springs, c' c' , one at each end, which keep the fingers or teeth of the bar between 20 the strings when not in use.

To provide for convenient and ready ascertainment of the required trigger to be pushed for any of the chords, a series of numbers or other characters representing the chords may 25 be placed upon the side a' , directly in front or in line with the ends of such triggers, as shown at D, Fig. 2. Such trigger-bars C themselves select the accompaniment—*i. e.*, the different tones of the various chords—so that the performer, by simply gliding over all the strings 30 and changing the trigger-bars, can perform as many arpeggio chords as are provided for in the trigger-bars, the number of which is not limited and may embrace the harmonies of all 35 scales.

The trigger C' represents the flageolet or octave trigger, and is adapted and designed to be pushed in the direction indicated by arrow y , or the reverse of that in which triggers C 40 are moved. Such arrangement is merely for the convenience of the harpist, and is not therefore a necessary one, as all of said triggers may, if desired, be moved in the same direction. When such flageolet-trigger is moved 45 as described all of its depending fingers come into contact with all of the strings of the harp, respectively, as illustrated in Fig. 3, such contacting of all of the strings of the instrument having the effect of temporarily shortening them. Consequently when they are then 50 vibrated they give a note in a higher key, and a melody then played thereon will be rendered in one of the octaves. It is for this reason that I term such trigger the "flageolet" or "octave" trigger.

It will be noticed that bar C' is arranged transversely over the middle of all the strings of the instrument and so adjusted that when moved its triggers touch them lightly at such 60 point, thereby producing the falsetto or flageolet tone.

If desired, the strings of the harp may be numbered and such numbers placed upon the triggers, as shown at e, Fig. 1. Such method 65 of so numbering the strings upon the triggers

may be that copyrighted to me January 3, 1871; or any other suitable or desired notification of such strings may be employed. Such figures or numbers are used instead of notes. When the strings are so noted or characterized the 70 harp may then be mechanically played or performed upon in all the various scales and chords by a person unfamiliar with the harp, provided such person be furnished with numbered or characterized music corresponding 75 to the notification placed upon the triggers. For this reason I denominate a harp provided with the said described triggers and numbered strings or scale marked thereon an "autoharp." When the triggers are not in use the springs 80 c' c' keep their depending fingers out of contact with the harp-strings, so that, if desired, the latter may be manipulated in the usual or customary manner.

It is evident that my invention is entirely 85 different from the pedals of a harp, or devices to take the place of such pedals, which merely change the vibration, length, and tone of the strings without rendering any of them silent, while my trigger-bars are employed to do the 90 work heretofore done by the performer with the left hand. The latter in my instrument does not need to be used for the accompaniment, the tones of the different chords being 95 given by the different trigger-bars.

What I claim as my invention is as follows:

1. The combination, with a harp of the form substantially as shown and described, of a series of bars, C C, arranged transversely across the strings thereof, and provided with depending teeth or fingers designed and adapted to come in contact with and silence or "cut out" certain strings when said bars are moved, substantially as set forth.

2. In a harp of the form substantially as 105 shown and described, the combination of trigger-bars C and C', the latter being placed transversely across the middle of the strings of the harp, substantially as shown, and for the purpose set forth.

3. In combination with harp A, the transversely-arranged triggers C C', provided with depending fingers or teeth c^2 , resting at one end against springs c' c' , substantially as shown, and for the purpose set forth.

4. The combination, with a harp of the form shown and described, of a series of trigger-bars arranged transversely across the strings of said harp, and constructed, substantially as shown and described, for silencing certain 120 strings thereof, substantially as and for the purpose set forth.

In testimony that I claim the foregoing I have hereunto set my hand this 9th day of December, 1881.

CHARLES F. ZIMMERMANN.
